Attorney.

UNITED STATES PATENT OFFICE.

JOSEPH WOYAK, OF MILWAUKEE, WISCONSIN.

DOOR-HANGER AND MEANS TO PREVENT THE SWAYING OF DOORS.

No. 854,789.

Specification of Letters Patent.

Patented May 28, 1907.

Application filed March 12, 1907. Serial No. 362,040.

To all whom it may concern:

Be it known that I, JOSEPH WOYAK, a citizen of the United States, and a resident of Milwaukee, in the county of Milwaukee and State of Wisconsin, have invented certain new and useful Improvements in Door-Hangers and Means to Prevent Swaying of Doors; and I do hereby declare that the following is a full, clear, and exact description thereof.

The improvements consist in what is herein shown, described and claimed; the object of the invention being to provide slide-doors with simple, economical roller-hangers and sway-guards, in combination with housed tracks for the rollers and stay-rails engaging said guards, said invention being especially applicable to slide doors of freight cars.

Figure 1 of the accompanying drawings represents a side elevation of a slide-door provided with fixtures in accordance with my invention, the track-housing for its roller-hangers, and the stay-rail for its sway-guards, said housing and rail being broken away. Fig. 2 of said drawings represents a transverse sectional view indicated by lines 2—2 in Fig. 1.

Referring by letter to the drawings, A indicates a sliding-door provided with hangers each comprising a pair of angular plates B, C, fitting one upon the other and bolted to the door, the upper portions of the plates being suitably bent in opposite directions, to form housings for rollers D, E, that turn on an axle F mounted in parallel vertical portions of said plates and the recurved upper ends of same. The rollers run on the bottom track-portions of an angular housing G bolted or otherwise fastened to the side of a freight-car, barn-wall or other support having an opening therein for which the door serves as a sliding closure.

Bolted to the lower portion of the door are sway-guards, each of which preferably comprises a pair of angular plates H, I, fitting one upon the other, but in some instances the plate I will be a sufficient sway-guard. Each

plate H has its lower end bent inward at a right-angle to the remainder thereof to come under a flange of a T-rail J bolted to the car-side, wall or other support aforesaid, spacing-blocks K being employed between said rail and support. The companion-plate I is bent inward at a right-angle parallel to the lower edge of the door and then at a double right-angle to come under the flange of the rail J aforesaid, whereby outward sway of said door is prevented. The sway-guards also prevent vertical displacement of the door.

I claim:

1. The combination of a door, hangers in rigid connection therewith and each comprising a pair of angular plates fitting one upon the other, their upper ends being bent in opposite directions to form housings, an axle mounted in parallel vertical portions of the plates and the recurved upper ends of same, and rollers on the axle within the housings; tracks for the rollers, sway-guards rigidly secured to the lower portion of the door; and a stay-rail opposing said guards.

2. The combination of a door, roller-hangers in rigid connection therewith, a roller-track, a plate fastened to the door and bent to extend parallel to the lower edge of same and then at a double right-angle, and a stay-rail having a flange thereof engaging said guard.

3. The combination of a door, roller-hangers in rigid connection therewith, a roller-track, sway-guards each comprising a pair of angular plates fitting one upon the other in rigid connection with the door, and a stay-rail having flanges with which the ends of the sway-guard plates are parallel under the same.

In testimony that I claim the foregoing I have hereunto set my hand at Milwaukee, in the county of Milwaukee and State of Wisconsin in the presence of two witnesses.

JOSEPH WOYAK.

Witnesses:

F. S. SMITH,
EDWARD KUNOVSKI.
